UNITED STATES PATENT OFFICE.

GEORGE J. SCHIED, OF ROCHESTER, NEW YORK.

PLAYING-CARDS.

1,243,985.

Specification of Letters Patent. Patented Oct. 23, 1917.

Application filed February 21, 1917. Serial No. 149,992.

To all whom it may concern:

Be it known that I, GEORGE J. SCHIED, of Rochester, in the county of Monroe and State of New York, have invented certain new and useful Improvements in Playing Cards; and I do hereby declare the following to be a full, clear, and exact description of the same, reference being had to the accompanying drawings, forming a part of this specification, and to the reference-numerals marked thereon.

My present invention relates to games and toys and it has for its object to provide a pack or deck of playing cards by means of which several amusing and instructive games may be played to the educational advantage of children and others. The invention contemplates the unconscious instruction or drill of the player in both spelling and counting at the same time increasing his familiarity with all the letters of the alphabet in their different usual styles and with the numbers. To these and other ends the invention resides in certain improvements and combinations of parts all as will be hereinafter more fully described, the novel features being pointed out in the claims at the end of the specification.

In the drawings:

30 Figure 1 is a representation of three cards of each of the four suits of twenty-six cards each that I prefer to employ in the practice of my invention, the suits being arranged in vertical rows;

35 Fig. 2 represents in a horizontal row four of the ten numeral cards used in one of the games for which the invention is adapted.

The deck consists of 104 cards divided 40 into 4 suits of contrasting colors. In the drawings, the cards of the first suit are indicated by 1, of the second suit by 2; of the third suit by 3, and of the fourth suit by 4. There are 26 cards to a suit and each 45 card bears a letter of the alphabet so that all of the 26 letters are represented in each suit. Aside from the difference in color previously mentioned, the style of the letters is different in each suit. In the present instance, the cards of the first suit bear capital block or print letters in black; those of the second group block or print letters in yellow; those of the third suit capital script letters in red, and those of the fourth suit, 50 small script letters in blue. In each instance, there may be a letter of large proportions in the center of the card and

smaller letters in opposite corners, as shown in the drawings.

There is a variety of games more or less 60 similar to each other that can be played; but the fundamental theme of each is the spelling of words by the players by combinations of the letters of the cards composing his hand and it is not believed to be 65 necessary to go into detail as to the rules that have been devised for each game or to more than generally point out the discriminations that may be made in governing the 70 relative values of the hands. The four sets of alphabets make it possible for a player to hold the proper cards to spell most any word, even though it may contain double letters or four appearances of the same letter. As no two cards have the same letter 75 in the same style or formation, values may be assigned to the hand accordingly as a word spelled by that hand appears in one or another type of letters. For instance, in accordance with one game that has been 80 devised, a hand is of value according to the number of letters in the word that is spelled. If it consists of a mixture of all of the four styles of letters or of two or three 85 of them, it has no added value; if it is composed entirely of small script letters of the fourth suit, it is of greater value; if it begins with a capital script letter of the third suit and the rest are small script letters of the fourth suit, it is of greater value and 90 higher values may be similarly allotted to all capital script letters, small block or print letters, small block or script letters beginning with a capital, or all block capitals of the first suit, the latter representing 95 the highest hand. These values are, of course, arbitrarily relative and, of course, may be interchanged as desired and made to modify or combine with the values derived 100 from the number of letters in the word that is spelled.

The hands may be formed and new cards introduced to complete them in any of the ways common to card games. They may be dealt around in installments or drawings 105 made from the deck or traded between the hands and discards may be drawn or dealt over again as desired. Also, hands may be called and compared to terminate a period or determine a count of a play or counts 110 may be aggregated according to the values of each hand without a comparison of the hands. When a player is unable to spell a word at the conclusion of a hand or when

a call is made, he may be set back a certain number of points according to the contents of his hand or the value of the winning hand. All these matters relate to the process of the game rather than to the characteristics of the cards and my invention is not limited to any of these rules of procedure which are not related to my improvements in playing cards except in so far 10 as they illustrate the wide range of useful application and amusement that the nature of the pack or combination of cards that I provide can produce.

The use of the cards so far described acquaints the player with the different letters and with the different styles of letters and drills him in the spelling and formation of words. To similarly teach the numerals, I provide the series of ten cards, four of 20 which are represented in Fig. 2. The game as heretofore explained, presupposes the selection of any word by a player such, for instance, as would best suit the contents of his hand. With the cards of Fig. 2 introduced into the game, each player is restricted to the formation of a word of a certain number of letters or, by another rule, of certain specific words containing a certain number of letters. The said cards of 30 Fig. 2 each bear a numeral from "1" to "9" and zero and each contains one or more words comprising a number of letters indicated by the numeral on the card. One card is dealt to each player with his hand 35 and his aim is to endeavor to spell a word on his card or a word of the number of letters indicated by the numeral on the card. In the present instance, the zero is assigned words of ten letters and the number "1" 40 card bears no words. The latter card may be considered to authorize the player to spell any word or, say, any word containing more or less than three, four or five letters. It is possible to shuffle the numeral cards with 45 the letter cards and make the restrictions as to words or numbers of letters a matter of chance.

From the foregoing, it is believed, the possibilities of my novel pack of cards will 50 be understood. They have a wide range of usefulness in the matter of elasticity in the rules that govern play, whereas they bring before the player all the different letters and all the different numerals and lead to exercise in the use of the latter and in the correct formation of words. It may also be pointed out that by using only the first 55 thirteen cards of each alphabet or suit, a deck of 52 cards may be made up having 60 relative values as to suits and units in the suit that permit of use for playing any of the known games for which ordinary playing cards are adapted.

I claim as my invention:

1. A pack of playing cards comprising a 65 plurality of suits, each suit constituting an alphabet of which the respective letters are arranged one on each card of the suit, the letters of each suit being of a style different from the letters of the other suit 70 or suits.

2. A pack of playing cards comprising a plurality of suits, each suit constituting an alphabet of which the respective letters are arranged one on each card of the suit, the 75 letters of each suit being of a style and of a color different from the letters of the other suit or suits.

3. A pack of playing cards comprising a plurality of suits, each suit constituting an 80 alphabet of which the respective letters are arranged one on each card of the suit, the letters of one suit being capitals and of another suit small letters.

4. A pack of playing cards comprising a 85 plurality of suits, each suit constituting an alphabet of which the respective letters are arranged one on each card of the suit, the letters of one suit being capitals and those of another suit small letters of a correspond- 90 ing type.

5. A pack of playing cards comprising a plurality of suits, each suit constituting an alphabet of which the respective letters are arranged one on each card of the suit, the 95 letters of one suit being block type and those of another script type.

6. A pack of playing cards comprising four suits, each suit constituting an alphabet of which the respective letters are ar- 100 ranged one on each card of the suit and the types of letters of the four alphabets being, respectively, capital block, small block, capital script and small script.

7. A pack of playing cards comprising 105 four suits of different colors, each suit constituting an alphabet of which the respective letters are arranged one on each card of the suit and the types of letters of the four alphabets being, respectively, capital 110 block, small block, capital script and small script.

8. A pack of playing cards comprising a plurality of suits, each suit constituting an alphabet of which the respective letters are 115 arranged one on each card of the suit, the letters of each suit being of a style different from the letters of the other suit or suits, in combination with a set of cards each bearing a numeral and a word, the latter 120 composed of the number of letters represented by the numeral.
